CLAIM(51) LOC (7) Cl. **15-03**

The ornamental design for a hydraulic breaker, as shown and described.

(52) U.S. Cl. **D15/21****DESCRIPTION**

(58) Field of Search D15/10, 21; 173/171, 173/162.1, 119, 134, 135, 21, 78

FIG. 1 is a perspective view showing a frontal side of the hydraulic breaker of the invention;

(56) **References Cited**

FIG. 2 is a front elevational view of the hydraulic breaker;

U.S. PATENT DOCUMENTS

FIG. 3 is a rear elevational view of the hydraulic breaker;

3,792,738 A * 2/1974 Mori et al. 173/119
4,018,291 A * 4/1977 Anderson 173/135
4,993,500 A * 2/1991 Greene et al. 173/21
D326,857 S * 6/1992 Ikeda et al. D15/21
5,134,989 A * 8/1992 Akahane 173/134

FIG. 4 is a left side elevational view of the hydraulic breaker (right side elevational view is a mirror image of the left side elevation view);

FIG. 5 is a top plan view of the hydraulic breaker; and,

FIG. 6 is a bottom plan view of the hydraulic breaker.
